UNITED STATES PATENT OFFICE.

SIGMUND L. GOLDMAN, OF CHICAGO, ILLINOIS.

BOTTLE-CLOSURE-APPLYING DEVICE.

Application filed January 3, 1922. Serial No. 526,738.

To all whom it may concern:

Be it known that I, SIGMUND L. GOLDMAN, a citizen of the United States, residing at Chicago, in the county of Cook and State 5 of Illinois, have invented a new and useful Improvement in Bottle-Closure-Applying Devices, of which the following is a specification.

My invention relates generally to bottle-closure-applying devices as, for example, for applying caps to bottles, though it is not to be limited thereto. My primary objects are to provide a novel, simple and inexpensive construction of closure-applying device of 15 the type employing a base supporting an upright member, the latter more particularly a rack, and from which upright member the movable closure-engaging element of the device is supported; to provide a novel, simple 20 and inexpensive construction of slide for co-operation with the upright supporting it and through the medium of which the closure-engaging portion is supported; and other objects as will be manifest from the 25 following description.

Referring to the accompanying drawings:

Figure 1 is a perspective view of a bottle-capping device constructed in accordance with my invention. Figure 2 is an enlarged 30 broken vertical sectional view taken through the slide portion of the device. Figure 3 is a section taken at the line 3—3 on Figs. 1 and 2 and viewed in the direction of the arrows; and Figure 4, a section taken at the 35 lines 4 on Figs. 1 and 2 and viewed in the direction of the arrows.

Referring to the construction shown in the drawings, the base of the device, and represented at 9, comprises a plate 10 shown 40 as of substantially rectangular form containing openings 11 therethrough for receiving screws, or other fastening means (not shown) for attaching the device to a table or the like as desired. The plate 10 adjacent 45 one end is provided at opposite sides with upwardly-extending plate-sections 12 provided with flanges 13 at their rear edges extending toward each other, these flanges reaching short of the bottom of the plate 10. 50 The rear edge of the plate 10 is provided with a plate portion 14 which extends upwardly and directly below, and closely adjacent to, the flanges 13. The parts described 55 are preferably formed integrally from a single sheet of metal punched and bent to present the related parts as described.

Rising from the base 9 is an upright represented generally at 15, this upright being formed of a bar 16 provided along one edge with rack teeth 17 and secured in flatwise-opposed position between a pair of bracket-forming bars 18, the bars 16 and 18 being secured together as through the medium of the rivets 19 passing therethrough. Each of the bars 18 is shown as provided with a substantially flat vertical portion 20 at its upper end at which it flatwise opposes the bar 16 and with an outwardly-inclined portion 21 between its ends, and with the straight vertical portion 22 at its lower end, the portions 21 diverging downwardly relative to each other, as represented, and forming a bracket structure, the lower portions 22 of which extend into the corners provided between the plates 12 and the flanges 13. The upright 65 structure described is shown as pivotally connected at the portions 22 with the plates 12, as through the medium of the pivots 23, adapting the upright to be swung from a position in which it extends parallel with the 70 plate 10 into a position in which it extends at right angles thereto, as shown in the drawings, and vice versa. Locking means for releasably holding the upright in vertical position are shown, these means comprising a bar 24 of rectangular shape in cross-section which extends through, and is vertically movable in, slots 25 in the portions 22 of the bracket, the ends of the bar 24 being adapted to enter slots in the upper edges of 75 the plate portions 12, as represented of the one end of the bar 24 in Fig. 1. When it is desired to swing the upright to horizontal position the user lifts the bar 24 to disengage the ends of the latter from the notches 80 26 and thereupon swings the upright to the position stated and when it is desired to move the upright to vertical position the operator merely swings the upright to such position, the bar 24 automatically dropping 85 into the notches 26.

Cooperating with the rack portion of the upright is a slide represented at 27, this slide, in the particular construction shown, being formed of a U-shaped member 28, 90 shown as bent from a single sheet of metal, and presenting side walls 29 and a rear connecting wall 30. The member 28 contains a spacer-block 31 shown as located between the walls 29 of the member 28 and spaced 95 at its rear edge from the wall 30, this block being rigidly secured in position as by 100 105 110

means of the rivets represented at 32 passing therethrough and through the side walls 29. Located above the block 31 and extending between the side walls 29, is a lever 33 shown as formed of two bar portions 34 extending in flatwise opposed relation, with a handle portion 35 shown as formed of a sheet of metal bent into general U-shape and affording at its rear end the spaced 10 apart portions 36 into which the front ends of the bars 34 extend in flatwise-opposed relation, these parts being rigidly secured together as through the medium of the rivets 37. The lever 33 which is pivotally supported 15 on the slide 27, as hereinafter described, is provided at its rear end with a gear segment 38, the teeth forming this segment being cut from the metal of the flatwise-opposed bars 33. The gear segment 38 20 meshes with the rack 17 in the assembled position of the upright 15 and slide 27, and by rocking the lever 33 on the slide 27, the latter is caused to move up or down on the bar 16, depending on the direction in which the 25 lever is rocked.

The pivot for the lever 33 is shown as in the form of a bolt 39 which extends through the side walls 29 of the slide 27 and the plates 34, the side walls 29 being clamped between the head 40 of the bolt and the nut 41 screwing on the threaded end thereof. The inner surfaces of the side walls 27 are recessed concentrically with the bolt 39, as represented at 42, to receive spring washers, 30 represented at 43 and surrounding the bolt 39, these recesses being preferably provided by outwardly deflecting the metal of the side walls 27 as shown. In the drawing up of the bolt 39, the spring washers 43 are 35 placed under tension and afford frictional resistance to the turning of the lever 33 on its pivots, the frictional resistance offered by these spring washers being preferably sufficient to cause the lever 33 to remain in any position in which it may be adjusted 40 about its pivot.

The teeth 38 on the lever 33 are so disposed that when this lever is swung into substantially upright position, these teeth 50 will be out of engagement with the rack 17 thereby permitting the slide 27, together with the parts carried thereby, to be raised and lowered on the bar 16 by merely pushing upwardly on the slide or permitting it to gravitate on this bar. In order that the upper portion of the slide 27 shall present guiding means for the slide 27 in its application to the bar 16, the lever 33 is provided with a surface which opposes, and extends closely adjacent to, the tooth portion 55 17 of the bar when the lever 33 is swung to a position in which its teeth 38 are out of engagement with the teeth 17. The surface just referred to and which is shown 60 so arranged as to extend substantially paral-

lel with the bar 16 when the lever is in the position last stated, is represented at 44, the lever 33 being provided with stop surfaces shown as in the form of flanges 45 bent outwardly from portions of the metal 70 forming the bars 34 which bear against the upper edges of the side walls 29, preventing further rotation of the lever 33 in anti-clockwise direction in Fig. 2, when the surface 44 extends parallel with the bar 16, 75 the flanges 45 also serving as stops, engaging with the lower lateral edges of the side walls 29, in the downward movement of the lever 33.

The slide 27 is provided with a bottle-closure-engaging portion provided, in the particular arrangement shown, for receiving a metal cap to be applied, and secured to, the mouth of a bottle. In the construction shown this portion is formed of a separate inverted cup-shaped member 46, with the lower edges of its wall flaring outwardly, the cup containing a cushion 47 of resilient material. The member 46 bears at its upper, closed, end flatwise against laterally-extending lugs 48 shown as formed integrally with the side-walls 29, the member 46 also resting flatwise against the under side of the spacer block 31, and being rigidly secured to the lugs 48, as by means 90 of the rivets 49 passing through these lugs and into the member 46.

It will be understood that in the use of the device the bottle to which the closure (not shown) is to be applied, is positioned 100 on the base plate 10, the closure applied to the member 46, and the lever 33 thereupon rocked to lower the slide 27 and force the closure to position on the bottle.

While I have illustrated and described 105 my invention as embodied in a certain particular form of structure, I do not wish to be understood as intending to limit it thereto as it may be embodied in various other forms, and various modifications and alterations of the form shown may be made, without departing from the spirit of my invention.

What I claim as new, and desire to secure by Letters Patent is:

1. In a bottle-closure-applying device, the combination of an upright provided with a rack portion, a slide on said upright and provided with portions which oppose the side walls of said upright and form guiding surfaces for said slide, and a handle-equipped gear segment pivoted on said slide and meshing with said rack, the teeth of said segment being so disposed that when the latter is rotated to a position in which its handle extends upwardly the teeth of said segment will be out of engagement with the teeth on said rack, said gear segment having a portion so positioned as to engage with said slide and limit the rotation of 120 125 130

said gear segment in a direction for disengaging it from said rack portion after said gear segment disengages from said rack-portion.

5 2. In a bottle-closure-applying device, the combination of an upright having a rack portion, a slide on said upright, a lever pivotally supported on said slide and having a gear segment engaging said rack, said

lever comprising two plates secured together 10 in flatwise relation, each of said plates being toothed to afford said gear segment, and lugs formed from the metal of said plates and integral with the latter extending from said lever and adapted to engage the body 15 portion of said slide when said lever is moved to a certain position.

SIGMUND L. GOLDMAN.
